UNITED STATES PATENT OFFICE.

OSCAR E. BRAY, OF TORONTO, CANADA, ASSIGNOR OF ONE-HALF TO
EDWARD G. E. FFOLKES, OF SAME PLACE.

DESIGN FOR A KNIFE-WHEEL.

SPECIFICATION forming part of Design No. 28,945, dated June 28, 1898.

Application filed February 14, 1898. Serial No. 670,332. Term of patent 7 years.

To all whom it may concern:

Be it known that I, OSCAR EZRA BRAY, a subject of Her Majesty the Queen of Great Britain, residing at the city of Toronto, in the 5 county of York and Province of Ontario, Canada, have invented and produced a new and original Design for a Knife-Wheel for Use in Ensilage-Cutters, of which the following is a specification, reference being had to the accompanying drawings, in which—

Figure 1 is an elevation of the knife-wheel, and Fig. 2 is a sectional view taken on the line *x y* in Fig. 1.

As shown in the drawings, the distinctive 5 feature of the design lies more particularly in the L-shaped spokes *l*, the short arm of the L being connected with the hub and the long arm with the rim, and from said angle of the L to the rim extend the shorter spokes *o*.

Brackets *s* are secured to the rim of the wheel, 20 which rim is beveled on its inner surface, as shown in the right-hand figure of the drawings.

The essential feature of the design consists more particularly in the L-shaped spokes; 25 secondarily, in the L-shaped spokes *l*, combined with the shorter spokes *o*, extending from the angle of the L to the rim.

Having described my invention, what I claim as new, and desire to secure by Letters 30 Patent, is—

The design for a knife-wheel, as herein shown and described.

Toronto, February 9, 1898.

OSCAR E. BRAY.
